CLAIM

The ornamental design for a shoe sole as shown and described.

DESCRIPTION

FIG. 1 is a top perspective view of a shoe sole, showing my new design;

FIG. 2 is a bottom perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top plan view thereof; and,

FIG. 8 is a bottom plan view thereof.

The broken lines in the figures are for the purposes of illustrating portions of the shoe sole, which form no part of the claimed design.

The 'NORTIV8' logo shown on the outsole of the shoe sole is a registered trademark of Top Glory Trading Group Inc.

1 Claim, 6 Drawing Sheets
